UNITED STATES PATENT OFFICE.

GEORGE R. WINSLOWE, OF ROCHESTER, NEW YORK.

DESIGN FOR AN APRON.

49,502:

Specification for Design.

Patented Aug. 8, 1916.

Application filed March 8, 1915. Serial No. 12,970. Term of patent 14 years.

To all whom it may concern:

Be it known that I, GEORGE R. WINSLOWE, a subject of the King of Great Britain, residing at Rochester, in the county of Monroe and State of New York, have invented a new and original and ornamental Design for Aprons, of which the following is a specification.

Figure 1 is a perspective view of the apron as viewed from the front. Fig. 2 is a perspective view of the apron as viewed from the rear.

The apron is made of such size as to completely encircle the body and is provided with arm and neck holes. A vertical row of buttons and button holes for joining the front and side of the apron appears at the front and a horizontal belt appears at the back, which belt is set to give the apron a smooth appearance at the front.

I claim.

The ornamental design for an apron as shown and described.

In testimony whereof I affix my signature in presence of two witnesses.

GEORGE R. WINSLOWE.
